UNITED STATES PATENT OFFICE.

DAVID HINDAHL, OF CHICAGO, ILLINOIS, ASSIGNOR TO H. STILLSON HART, OF CHICAGO, ILLINOIS.

MAXIMUM-CAPACITY CAR.

Application filed July 3, 1924. Serial No. 723,861.

To all whom it may concern:

Be it known that I, DAVID HINDAHL, a citizen of the United States, residing at Chicago, in the county of Cook and State of Illinois, have invented certain new and useful Improvements in Maximum-Capacity Cars, of which the following is a specification.

The present invention relates to maximum capacity cars.

More particularly the present invention relates to the construction of railway dump cars. Cars of this sort are commonly designed to deposit lading selectively outside 15 of the tracks or between the tracks between the trucks, which trucks are located adjacent to the two ends of the cars. If the lading to be deposited is relatively heavy, such, for example, as rock ballast, the carrying capacity for such lading is limited not by the bulk thereof but by the weight. Ballast cars in common use limit the amount of rock ballast or other heavy ballast to that which may be carried by said car at regions from 20 which dumping may be conveniently accomplished between the trucks. Inasmuch as the distance between the trucks is limited by certain specifications, a problem which has presented itself to designers of cars of 25 this sort has been to so design the parts that a maximum of ballast up to the limit of weight may be carried without sacrificing the advantages of convenient dumping and without sacrificing adaptability for the car 30 for carrying lighter lading. Certain types of ballast cars which have been designed are quite inefficient when it is desired to carry other lading such as coal, which is lighter in weight, inasmuch as said cars do not 35 economically utilize the space over the trucks.

The present invention relates to the same general subject matter as application Serial No. 696,114, filed by the present applicant 45 March 1, 1924, and has for one of its objects the provision of a car of improved sturdiness.

A further object is to provide a car which will permit the carrying of a maximum of 50 heavy lading up to a limited weight, which car will also be efficient for carrying lading of lighter weight.

A further object is to provide an all steel 55 car for carrying a maximum of heavy lading, such as rock ballast, which should be

deposited selectively between the rails or outside of said rails and for carrying lading such as coal, which need not be dumped between the rails.

Further objects will appear as the description proceeds.

Referring to the drawings—

Figure 1 is a longitudinal sectional view of a railway dump car embodying the principles of the present invention; and

Figure 2 is a transverse sectional view taken along the plane indicated by the line 2—2 of Figure 1.

The numeral 1 indicates a dump car having the side walls 2—2 and end walls, one of 70 which is indicated by the numeral 3.

Trucks, one of which is located adjacent to each end of the car, are illustrated diagrammatically by the wheels thereof, which wheels are indicated by the numerals 4—4. 75 According to the illustrated embodiment of the present invention, the car is provided with dumping mechanism located between the trucks, said dumping mechanism comprising doors, one of which is indicated in 80 part of its length in Figure 1, said door bearing the numeral 5. Said doors 5 are mounted for swinging movement about axes disposed longitudinally of the car.

The mechanism and arrangement of the 85 dump doors between the trucks need not be illustrated or described, inasmuch as dumping mechanism for the purpose is well known. It will be sufficient to state that the dumping mechanism between trucks will 90 preferably permit the selective dumping either between the rails upon which the car is mounted or outside of said rails.

Each end of the car is provided with a 95 sloping floor 6, which floors 6 slope toward the adjacent ends of the doors 5, that is to say, said floors 6—6 are so sloped that lading located above said floors will tend to move toward said doors 5 when said doors are opened. Said floors should be disposed 100 at such an angle relative to a horizontal plane that such lading as rock ballast will flow therefrom, that is to say, the angle should be such that the force of gravity acting upon rock ballast located above said 105 floors will be sufficient to overcome the resistance to flow due to contact between the floors 6—6 and the ballast resting thereon.

For this purpose it has been found by experiment that the angularity of the floors 110

6—6 relative to a horizontal plane may be approximately 45 degrees with the car standing upon a horizontal track, in case said car is intended for the carrying of rock ballast.

At each end of the car above the trucks is a floor indicated by the numeral 7. The details of construction of the floors 7 do not form a part of the present invention, but 10 said floors should be so designed as to permit the discharge of lading therefrom to the sides of the car outside of the rails. Any preferred design of floor may be used, many of such designs being known to those skilled 15 in the art. According to the illustrated embodiment of the present invention, the floors 7 may comprise sloping portions for directing lading laterally of the car, said sloping portions having their apex along the line marked by the angle 8. Swinging side doors 20 9—9 may be provided, controlled in any preferred way, for permitting lading to flow from said floors 7 to the sides of the car. Cooperating with each sloping floor 6 is the 25 reversely sloping floor or wall 10, which floors 10—10 are provided for the purpose of supporting lighter lading at the ends of the car. Each sloping floor 6 extends to a line disposed transversely of the car, which 30 line lies near the top of the car above the corresponding truck indicated by the wheels 4—4. In the illustrated embodiment of the 35 present invention the top of each floor 6 lies in a vertical plane substantially mid-way between the wheels 4—4 of its adjacent truck. The upper edge of each floor 6 will be provided with an angle 11, one flange of 40 which underlies the corresponding floor 6 and the other flange of which extends upwardly toward the vertical transverse central plane of the car. Said angles 11—11 define the limits, longitudinally of the car, of 45 the lading carried centrally of said car, the outline of which lading is indicated by the numeral 12.

The numeral 13 indicates a bolster comprising the two channels 13'—13'. Said bolster is made use of in supporting the corresponding sloping floor 10. Mounted above 50 and below said bolster 13 are the transversely extending steel plates 14 and 14', the upper of which carries the transversely extending steel angular member 15. Said angular member 15 has a portion engaging 55 with the steel plate 14, preferably riveted to said plate and to the bolster 13, and another portion extending in the direction of the floor 10. Riveted to each floor 10 and to the corresponding angular member 15 is 60 the plate 16, which has a portion 16^a lying in a plane parallel to and adjacent to the plane of the corresponding floor 10. Each plate 16 also has a portion 16^b lying in a vertical plane, having edges conforming to 65 the floors 7—7 and to the side doors 9—9.

Said angular member 15 and plate 16 effectually prevent the lodgment of lading in the space between the floor 10 and the floor 6. Each sloping floor 10 is secured to the corresponding sloping floor 6 by means of 70 an angle 17, which may be riveted to said floors. Underlying each of the sloping floors 10 are braces 19, which may conveniently take the form of angles riveted to the corresponding floors 10. Said angles 75 may be bent at their lower ends, as indicated by the numeral 20, and may be riveted to the corresponding angular member 15, the corresponding plate 16 and corresponding floor 10. 80

In operation, when it is desired to use the car for carrying rock ballast or other heavy lading, said heavy lading will be deposited in the car centrally thereof, being carried by the bottom portion between the trucks and by the sloping floors 6—6, said heavy lading assuming an angle of repose, which may be indicated by the broken line 12. The angles 11—11 at the tops of the two sloping floors 6—6 are useful in stopping the passage of 85 ballast beyond the ends of said floors 6—6. Dumping of the ballast or other lading between the floors 6—6 will be accomplished by manipulation of the dumping mechanism at the bottom of the car, which dumping 90 mechanism includes the dump door 5. When the car is to be used for the purpose of carrying lading which need not be dumped between the tracks, the entire car between the end walls 3—3 thereof may be 95 filled with such lading, only a small portion of the car between the sloping floors 6 and 10 at each end of the car being unused at this time. That portion of the lading which is located on and between the sloping floors 100 6—6 will be dumped through the dumping mechanism including the doors 5—5. That part of such lading which is located between the floors 6—6 and the ends of the car will be directed through the swinging doors 105 9—9 (Figure 2). The car illustrated and described will shed all of the lading, whereby a maximum of convenience in handling 110 is obtained. Furthermore, due to the fact that the car is of all steel construction, a 115 minimum of space will be utilized for the material of the car and a maximum of sturdiness will be had.

Though a preferred embodiment of the present invention has been described in detail, it will be clear that many modifications may be made without departing from the spirit of the invention. It is intended in this patent to cover all such modifications that fall within the scope of the appended 120 claims.

What is claimed is:

1. In a dump car, in combination, a sloping steel floor for directing lading centrally of said car, and a sloping steel wall having 130

abutting relationship with the under side of said floor for directing lading to a region adjacent to an end of said car, said sloping floor being extended to a region materially above said sloping wall, the under side of said sloping wall being provided with bracing angles, bolster means extending transversely of said car at a region adjacent to the bottom portion of said sloping wall, said 10 sloping wall, angles and bolster means being riveted together to form a sturdy construction.

2. A dump car for efficiently carrying either relatively heavy or relatively light 15 lading, comprising a car body having a truck adjacent to an end thereof, dump means disposed centrally of said car, a sloping steel floor above said truck for directing lading to said dump means, means providing a receptacle at said end 20 of said car beyond said sloping floor, said receptacle including a floor for directing lading laterally of the car and a steel wall abutting against the under side of said 25 floor in angular relationship thereto, said last mentioned floor and said wall being

provided with angular connecting means, said car being provided with bolster means extending transversely of said car at regions adjacent to the bottom portion of said 30 sloping wall, said sloping wall, angles and angular connecting means being riveted together to form a sturdy construction.

3. A car of the class described having vertical sides and ends, intermediate inclined 35 floors extending from a point adjacent to the inner ends of the trucks upwardly toward the ends of the car, sloping floors extending upwardly from a point adjacent to the bolster to a point intermediate of the 40 ends of said intermediate inclined floors, a flanged member for connecting the lower ends of said sloping floors to the bolster cover plate, said member having an upper flange having an incline corresponding to 45 that of the sloping floor, a vertical flange, and a flange at right angles to said vertical flange for connecting said member to the bolster cover plate.

Signed at Chicago, Illinois, this 23rd day 50 of June, 1924.

DAVID HINDAHL.
